UNITED STATES PATENT OFFICE.

ADIEL VANDENWEGHE, OF NEW YORK, N. Y., AND AUGUST D'HUYVETTERS, OF RIDGEFIELD PARK, NEW JERSEY, ASSIGNEES TO IDEAL COONEY DRESSING & DYEING COMPANY, INC., OF PATERSON, NEW JERSEY, A CORPORATION OF NEW JERSEY.

APPARATUS FOR TANNING.

1,233,730.

Specification of Letters Patent. Patented July 17, 1917.

Application filed January 5, 1917. Serial No. 140,699.

To all whom it may concern:

Be it known that we, ADIEL VANDENWEGHE and AUGUST D'HUYVETTERS, citizens of the United States, residing at Bronx 5 borough and State of New York, and Ridgefield Park, Bergen county, and State of New Jersey, respectively, have invented certain new and useful Improvements in Apparatus for Tanning and the like, of which 10 the following is a specification.

This invention relates to the treatment of flexible materials by liquids, as in the tanning of hides or skins, and particularly to those methods in which it is a necessary 15 condition to the success of the treatment that the liquid be kept up to a certain temperature.

In one method of tanning hides, since 20 heating the tanning liquid with the hides therein is detrimental to the best results, it is necessary for the hides to be removed every time the liquid is brought up to the desired temperature. For instance, the 25 liquor is heated and the hides placed therein; then, when reheating is again necessary, the hides are removed and the heating of the liquor effected, whereupon the hides are returned to the liquor; and so on, several 30 times, until the aggregate time the hides are in the liquor is sufficient to complete the tanning process. The hides cannot be removed and returned to the liquor *en masse*, or a number at a time, because as an incident to handling they will adhere together, 35 which results in some of the hides being in places not perfectly acted upon by the liquor. Hence the entering of the hides into the liquor and removal therefrom has to be effected in a one-by-one manner, which is a 40 slow and tedious operation, requiring the employment of a number of attendants.

Our object by the present invention is to 45 simplify the tanning and similar treatments where several heatings of the liquor of treatment is necessary and to reduce to the minimum the labor and the number of attendants required, obtaining, at the same time, uniform tanning results as to each hide. This object we have attained by employing a novel apparatus, one form of 50 which by way of example is shown in the accompanying drawings, wherein,

Figure 1 is a transverse sectional view of

a building containing the apparatus which is shown also in transverse section;

55

Fig. 2 is a plan of said apparatus;

Fig. 3 is a front elevation thereof, partly in section;

Fig. 4 is a plan on a larger scale than Fig. 2, partly in section; and,

60

Figs. 5 and 6 are vertical sectional views on lines 5—5 and 6—6 of Fig. 4 looking in each case in the direction of the arrow adjacent the section line.

Along one side of and within the building 65 *a* a series of aligned vat-structures is built, each being constructed with four upright walls *b*, rectangularly arranged and reaching below the floor *c* of the building, a lower bottom wall *d* below the level of the 70 floor, and an upper bottom wall *e* above such level, so that there result two vats in each vat structure, one above the other. Over the lower vat is arranged a runway *f* which is substantially level with the floor *c*, 75 there being an opening *g* in the front wall of the vat structure formed to reach upward from the floor level more or less to the level of the bottom of the upper vat and having suitable width.

80

The tanning is accomplished in the upper vat, the lower vat being employed for heating the tanning liquor. Heating means *h* is shown in each lower vat, being in the present instance a coil of piping extending from 85 a steam pipe line *i* that is arranged under a platform *j* projecting from the front walls of the series of vat structures over the openings *g* therein. For transferring the tanning liquid to the lower vat for heating 90 and then returning the same to the upper vat we provide the following instrumentalities:

One or more drain outlets *k* for the liquor are provided in the bottom of the upper vat, being shown in the present instance as 95 simple holes provided with stoppers or plugs *k'* and arranged at the back corners of the upper vat; they are preferably separated from the main part of the vat by the screens *l* to keep the hides from being drawn into the holes *k* when draining. When the tanning liquor cools the attendant removes the plugs *k'*, allowing the liquor to flow down into the lower vat.

A stand-pipe *m* extends from the bottom of the lower vat through the bottom of

the upper vat and to a level above the maximum liquid level therein, being preferably covered by a mushroom-shaped cap *n*; it contains an upwardly directed injector *o* connected with the steam-line *i*. When the liquor, having been delivered to the lower vat, has been heated to the desired temperature therein, the steam is admitted to the injector by turning the valve *p*, resulting in 10 the heated liquor being driven up into the upper tank, the plugs *k'* having been of course again placed in stoppering relation to the holes *k*.

While the hides are undergoing the tanning process in the upper vat it is preferred 15 to keep the liquor and the hides therein in motion, so as to insure thoroughness and uniformity of the tanning action. This may be accomplished by the rotary agitator *q* 20 which dips into the liquor and may be driven by the means *r* shown in the drawings.

The tanning liquid concentrate is conveyed through pipe *s* from the tank *t*, to 25 which water may be delivered from the valved pipe *u*. From this pipe leads a branch pipe *v* having a series of valved outlets *w*, one over each upper vat in the series. By the pipe *v* water may be allowed to 30 enter each upper vat for washing the hides after the tanning process is completed. Each upper vat has an outlet *x* for draining off the washing water, the same being equipped with a drain pipe *y* which leads 35 to a waste pipe *z*. There is a plug or stopper *2* for this outlet which is tubular (Fig. 6). The plug being in stoppering relation in the outlet the upper vat can be flooded, the overflow running off through the plug, 40 and when the washing is completed the plug is withdrawn, so that the washing water can drain to the waste pipe *z*.

In the bottom of each upper vat is a relatively large outlet *3* having a plug *4*. 45 Through this outlet the hides are adapted to be delivered, when the treatment and the washing thereof is completed, into a suitable receptacle *5* adapted to be run in on the runway *f* under the outlet *3* to receive the 50 hides.

In the use of the apparatus, the concentrate is run into the upper vats, with water from the pipe *v* to properly dilute it, the tanning liquor resulting being allowed to 55 flow to the lower vats by withdrawing the plugs *k'*. In the lower vats the liquor is heated to the proper temperature by the heating means *h*. The steam is then admitted to the injectors and, the plugs *k'* being returned to stoppering relation to the holes *k*, the liquor is returned to the upper vats. The hides are then placed in the upper vats for a suitable length of time and when it is necessary to re-heat the liquor, 60 the plugs *k'* are again removed to allow the 65

tanning liquor to return to the lower vats and be there re-heated, the hides remaining in the upper vats. When the liquor has been re-heated, it is returned to the upper vats by the injectors so as to continue the 70 tanning process. These steps are repeated until the tanning of the hides is completed. The alternate draining of the tanning liquor from the tanning vats for the purpose of heating it separately from the hides and 75 then returning it to the tanning vats after re-heating effects a great saving in time and labor over the method now employed, which consists in removing the hides one by one from the tanning liquor in order to heat the 80 same, as will be obvious. After the tanning has been completed, the tanning liquor having been run into the lower vats or allowed to run by outlets *y* to the waste *z* by withdrawing plugs *2*, the water from the pipe *v* is turned into the upper vats and the plugs *2* being in stoppering relation to the outlets *x* it overflows said tubes and drains off therethrough to the waste pipe *z*, the washing in this way being continued till the 85 tanning liquor remaining on the hides has been sufficiently carried away. Thereupon plugs *2* are removed and the vats drained of the washing water. Finally, the hides being now tanned and washed, the receptacles 90 *5* are run through the openings *g* onto the runways *f*, the plugs *4* are removed and the hides raked to the openings *3*, where they fall into the receptacles, by which they may then be carried to the place where they are 100 to receive further treatment.

Having thus fully described our invention, what we claim as new and desire to secure by Letters Patent is:—

1. In an apparatus for treating hides and 105 similar materials with liquors, the combination of a vat to receive the liquor of treatment and in which to treat the materials, a liquor heating vat under the first vat, the first vat having a drain to the second vat, 110 means to heat the liquor in the second vat when the same has been drained from the first vat into the second vat, means to deliver the heated liquor back from the second vat into the first vat, the first vat having an 115 outlet in its bottom for the materials, and means under said outlet and over the second vat to receive a receptacle for the materials delivered from said outlet.

2. In an apparatus for treating hides and 120 similar materials with liquors, the combination of a liquor receiving structure comprising upright side walls and upper and lower vat-bottom walls, the side walls with said bottom walls forming an upper vat to receive 125 the liquor of treatment and in which to treat the materials and a lower liquor-heating vat and one side wall having an opening between the vats affording access to the lower vat above the liquor level therein, and the 130

first vat having a liquor drain to the second vat, means to heat the liquor in the second vat when the same has been drained from the first vat into the second vat, means 5 to deliver the heated liquor back from the second into the first vat, the first vat having an outlet in the bottom for the materials, and means under said outlet and over the

second vat adapted to receive a receptacle for the materials delivered from said outlets. 10

In testimony whereof we affix our signatures.

ADIEL VANDENWEGHE.
AUGUST D'HUYVETTERS.
